H. R. ROBBINS,
Press and Former for Making the Heads of Sheet-Metal
Cans.

No. 228,120.

Patented May 25, 1880.

UNITED STATES PATENT OFFICE.

HENRY R. ROBBINS, OF BALTIMORE, MARYLAND, ASSIGNOR TO HIMSELF,
JAMES E. STANSBURY, AND JOHN B. STANSBURY, OF SAME PLACE.

PRESS AND FORMER FOR MAKING THE HEADS OF SHEET-METAL CANS.

SPECIFICATION forming part of Letters Patent No. 228,120, dated May 25, 1880.

Application filed January 30, 1880.

To all whom it may concern:

Be it known that I, HENRY R. ROBBINS, of Baltimore city and State of Maryland, have invented a new and Improved Press and 5 Former for Making the Heads of Sheet-Metal Cans; and I do hereby declare that the following is a full, clear, and exact description of the same, reference being had to the accompanying drawings, forming part of this 10 specification, in which—

Figure 1 is a vertical section. Fig. 2 is another vertical section taken in a plane at right angles to that in which Fig. 1 is taken, and showing in dotted lines the position of the 15 plunger or male die when at the end of its downstroke. Fig. 3 is a detail sectional view of the can-head, which is the product of the machine. Fig. 4 are details of the sectional ring, the parts being disconnected.

20 My invention relates to a novel form of press for forming a special construction of can-head, which head is made in one piece, with a skirt or flange at right angles to the main portion, and with a swell or bulge at the corner.

25 My press for forming this peculiar head consists in the usual male and female die, combined with a detachable segmental ring in the upper edge of the female die for forming the contracted skirt of the head, together with a 30 pair of formers in the male die and means for projecting them radially outward into the groove formed by the detachable ring of the female die, and also means for rotating the said female die, so as to cause the partially-formed blank to be traversed by the formers to make the bulge or groove therein at the 35 point where the edge of the shell joins the head, as hereinafter fully described.

The press for making these heads is composed of a stationary bed-block, C, a stationary top block, D, a rotary female die, E, and a reciprocating male die, F.

40 The female or lower die is made of a circular exterior, and rests in a circular recess of the bed-block upon a circular row of friction-balls, G, which balls are retained partly in an annular groove in the bed-block and partly in a corresponding annular groove in the bottom of the female die. Said female die is also provided with a downwardly-projecting spindle,

H, which passes through a central hole or bearing in the bed-block and connects below with mechanism (not shown) of any suitable character for turning the female die horizontally upon its balls. The upper portion of the female die is recessed with a circular cavity corresponding to the shape and depth of the can-head, and is provided with a segmental or sectional ring, I, in the lower portion of which is formed a groove, e.

55 The male die F, which is the counterpart of the female die, is provided with a stem, f, which rises through an opening in the top block, D, and connects with mechanism of any suitable character (not shown) adapted to give to the male die a vertical reciprocating movement. In the opposite sides of the male die are arranged curved and adjustable formers g, which extend through channels passing from the upper horizontal side of the male die to the 60 lower portion of the vertical side, so that their ends or toes rest, when the male die is down, in the same plane with the groove e of the female die.

65 These formers may be made either curved or straight, and are held up by springs h, and are normally withdrawn thereby into the channels of the male die, so that their lower ends do not project; but they are made capable of projection to cause their lower ends to traverse the groove of the female die and form the swell or bulge in the can-head. For thus projecting these formers the stem f of the male die is provided with a feather or spline, f', that slides in a corresponding groove in the 70 top block and prevents the male die from turning axially.

75 A bifurcated lever, J, is also hinged on top of the top block and arranged to bear upon two loose pins, i i, which slide through holes 80 in the top block and bear at their lower ends upon the top of the formers g, to cause them to be projected.

85 Now, in striking up the can-head, the disk of metal is placed between the male and female die, and the male die then brought down, forming the cup-shaped head of the can. Then the lever J is depressed and the formers g projected into the groove e, and simultaneously therewith the mechanism for rotating the lower 90

die is set in motion and the lower die carrying the now cup-shaped blank moves with said blank, and as the latter is carried over the projecting toes of the formers *g* the metal at this point is thrown out into the groove *e* and a bulge or swell formed in the head of the can. The male die is then raised, and the sheet-metal can-head and segmental ring are taken out together.

Having thus described my invention, what I claim as new is—

1. The combination of a stationary bed-block, a stationary top block, a rotary female die, and a reciprocating male die having formers adapted to be projected, substantially as described.
2. The combination, with the stationary bed-block having a circular recess with an annular

groove containing friction-balls *G* and a central opening, of the female die fitting in the recess of the bed-block and resting upon the friction-balls, and provided with a downwardly-projecting spindle passing through the bed-block for turning the said female die, as and for the purpose described.

3. The combination, with the female die having a groove, *e*, of the male die having curved formers *g*, held up by springs *h*, the top block having holes therethrough, with loose pins *i* and the lever *J*, adapted to press upon the tops of the pins to project the formers, substantially as described.

HENRY R. ROBBINS.

Witnesses:

EDWARD STARR,
SOLON C. KEMON.
